Dec. 9, 1930.

V. WILLOUGHBY

1,784,473

MINE CAR

Filed Nov. 20, 1929

UNITED STATES PATENT OFFICE

VICTOR WILLOUGHBY, OF RIDGEWOOD, NEW JERSEY, ASSIGNOR TO AMERICAN CAR AND FOUNDRY COMPANY, OF NEW YORK, N. Y., A CORPORATION OF NEW JERSEY

MINE CAR

Application filed November 20, 1929. Serial No. 408,501.

This invention relates to mine cars and more particularly to mine cars having bottoms formed of a plurality of dumping doors, and it is an object of this invention to provide an improved latching mechanism for the drop doors of cars of the type described, and it is also an object of this invention to provide a support for the latch operating means in cars of the type described which 10 serves also as a journal box for the car axle and as a support for the hood which shields the latching mechanism.

With these and other objects in view, as will appear more fully hereinafter, the invention consists substantially in the construction, combination, location and relative arrangement of the parts, all as will be more fully herein set forth, as shown in the accompanying drawings and finally pointed 20 out in the appended claims.

In the drawings:

Figure 1 is a partial vertical transverse section taken adjacent a car axle as on the line 1—1 of Fig. 3 of a drop bottom mine 25 car constructed in accordance with this invention, some parts being broken away to show other parts more clearly;

Fig. 2 is a view partly in top plan and partly in horizontal section, the section being 30 taken substantially on the center line of the axle;

Fig. 3 is a partial vertical longitudinal section taken as on line 3—3 of Fig. 1;

Fig. 4 is a partial vertical transverse section taken as on line 4—4 of Fig. 3;

Fig. 5 is a view in elevation of the combined journal box and support; and

Fig. 6 is a view in elevation of one of the latches.

In the drawings, which show only sufficient of the mine car to illustrate the application of this invention thereto, there is shown a mine car of the general type shown in patent to Field, No. 1,631,313, of June 7, 45 1927, and comprising a body having an end sheet 1 and a side sheet 2 supported upon a frame of which only a longitudinal sill 4 is shown. The frame is supported upon axles 6 having wheels 8 thereon, the axles 6 extending through openings in the longitudinal 50

sills 4 and being journaled in journal boxes 10 attached to the inner faces of the longitudinal sills 4. Each journal box 10 comprises a journal portion 12 and flat wing portions 14 by which it is secured to the inner face 55 of the vertical web of the longitudinal sill 4 by rivets 16, the rivets 16 also securing a reinforcing plate 18 to the outer face of the web of the sill 4. Surrounding the journal portion of the box 10 and formed integral 60 therewith is a substantially inverted U-shaped inwardly projecting flange having flaring side portions 20 united by a curved upper portion 22. At the bottoms of the flaring portions 20 and formed integral 65 therewith are arms 24 which converge and at their lower ends are united to form a hinge lug 26 having an opening 27 to receive a hinge pin 28. The hinge pin 28 also engages in openings in the ears 30 of the hinge strap 70 32 attached to a door 34 and secures the door 34 to the hinge bracket formed of the arms 24 and hinge lug 26.

As in the patent to Field referred to above, 75 operation of the door 34 controls the operation of an adjacent door 36. The door 36 is supported at its free edge by means of spaced latches 38 which comprise a link or arm portion 40 provided with an opening 42, which receives the axle 6, and with a shoulder or lip 44 upon which rests the free edge of the door 36. Each latch 38 is also provided with the spaced projecting ribs 46 which form a slot which, when the latches are in position, receives a lug 48 formed integral with one of the ears 30 of the adjacent hinge strap 32 and positioned eccentrically thereon with respect to the opening provided for the hinge pin 28. Each latch 38 is also provided with a shoulder 50 projecting oppositely to the ribs 46, 80 the shoulder 50 being arranged so that when a pair of latches 38 are positioned on an axle 6, as shown in Fig. 1, the shoulders 50 of the latches will extend toward each other and the ribs 46 will project outwardly. The 85 shoulders 50 are joined by an angle bar 52 having a horizontal flange 54 resting upon and attached to the shoulders 50 and a vertical flange 56 projecting downwardly in front of the free edge of the door 36. With the 90

angle bar 52 attached to the shoulders 50 the latches 38 will be held spaced apart on the axle 6 and the length of the angle bar 52 is such that the latches 38 will be held with the lugs 48 on the hinge straps 32 in engagement in the slots formed by the spaced ribs 46.

Each latch 38 is also formed with an opening 58 through which is inserted the hinge pin 28 and the hinge pin is retained in position in the hinge strap 32 by means of a cotter 60 and washer 62 which prevents movement of the hinge pin towards the center of the car, while movement of the hinge pin towards the side of the car is prevented by the sill 4. The shoulder 44 upon which the free edge of the door 36 rests projects some distance in advance of the vertical flange 56 of the angle bar 52 and in order to provide proper clearance between the latch and the door, the free edge of the door is partly cut away adjacent the latch 38.

To the flanges of oppositely placed journal boxes are attached hoods 64 which are shaped to fit the flaring sides 20 and curved upper portion 22 of the journal box flanges and at their lower edges are flared outwardly as at 66; the spread of the hoods being sufficient to cover the free edge of the door 36 and the inner or hinge edge of the door 34. The hood 64 also serves as a tie or brace between the sills 4.

In this construction, as in the patent mentioned above, operation of the end door of the car may be controlled by a suitable ramp (not shown) and the operation of the other doors is controlled by the operation of the door immediately in advance; that is, the dropping of the door 34 will operate through the lugs 48 to retract the latches 38, withdrawing the shoulders 44 from beneath the free edge of the door 36 and permitting the door 36 to drop. When the doors are closed by engagement with a suitable track ramp, as in the other construction, the door 36 is raised first and the door 34 is raised thereafter. Raising the door 34 causes the lugs 48 to operate the latches 38 to position the shoulders 44 beneath the free edge of the door 36 and in case the door 36 is not in its normal closed position the vertical flange 56 of the angle bar 52 will engage the free edge of the door and force the door 36 to its normal closed position; the angle 52 thus serving as an abutment to finally position the door 36 and also serving, together with the hood 64, to prevent leakage of the contents of the car past the free edge of the door 36.

While the preferred form of the invention has been shown and described, it is to be understood that the invention is not limited to the exact details of construction shown and described as it is obvious that various modifications thereof within the scope of the claims will occur to persons skilled in the art.

What is claimed is:

1. In a mine car having drop doors, wheels and axles, latches for one of said drop doors mounted on an axle, and means spacing said latches on said axle.

2. In a mine car having drop doors, wheels and axles, latches for one of said drop doors mounted on an axle, and means spacing said latches on said axle and serving as an abutment for said door.

3. In a mine car having drop doors, wheels and axles, latches for a drop door mounted on an axle, laterally projecting shoulders on said latches, and means connecting said shoulders.

4. In a mine car having drop doors, wheels and axles, latches for a drop door mounted on an axle, laterally projecting shoulders on said latches, and an angle member having a horizontal flange connecting said shoulders and a vertical flange projecting in front of the door controlled by said latches.

5. In a mine car having drop doors, wheels and axles, latches for a drop door loosely mounted on an axle, journal boxes for said axle, means carried by said journal boxes for operating said latches, and means connecting said latches and maintaining said latches in engagement with said operating means.

6. In a mine car having drop doors, wheels and axles, latches for a drop door mounted on an axle, journal boxes for said axle, means carried by said journal boxes for operating said latches, and a hood for said latches carried by said journal boxes.

7. In a mine car having drop doors, wheels and axles, latches for a drop door loosely mounted on an axle, journal boxes for said axle, means carried by said journal boxes for operating said latches, shoulders on said latches, and means connecting said shoulders and holding said latches in engagement with said operating means.

8. In a mine car having drop doors, wheels and axles, latches for a drop door loosely mounted on an axle, journal boxes for said axle, means carried by said journal boxes for operating said latches, shoulders on said latches, and an angle bar connecting said shoulders and holding said latches in engagement with said operating means.

9. In a mine car having drop doors, wheels and axles, latches for a drop door loosely mounted on an axle, journal boxes for said axle, means carried by said journal boxes for operating said latches, shoulders on said latches, and an angle bar connecting said shoulders and holding said latches in engagement with said operating means, said angle bar having a horizontal flange engaging said shoulders and a vertical flange extending in front of the door controlled by said latches.

10. In a mine car having drop doors, wheels and axles, latches for a drop door loosely mounted on an axle, journal boxes for

- said axle, means carried by said journal boxes for operating said latches, shoulders on said latches, means connecting said shoulders and holding said latches in engagement with said operating means, and a hood for said latches carried by said journal boxes. 5
11. In a mine car having drop doors, wheels and axles, latches for a drop door loosely mounted on an axle, journal boxes for said axle, means carried by said journal boxes for operating said latches, shoulders on said latches, an angle bar connecting said shoulders and holding said latches in engagement with said operating means, and a hood for said latches carried by said journal boxes. 10
12. In a mine car having drop doors, wheels and axles, latches for a drop door loosely mounted on an axle, journal boxes for said axle, means carried by said journal boxes for operating said latches, shoulders on said latches, an angle bar connecting said shoulders and holding said latches in engagement with said operating means, said angle bar having a horizontal flange engaging said shoulders and a vertical flange extending in front of the door controlled by said latches, and a hood carried by said journal boxes and shielding said latches and latch operating means. 15
13. In a mine car having drop doors, wheels and axles, journal boxes for said axles, and hinge lugs formed integral with said journal boxes. 20
14. In a mine car having drop doors, wheels and axles, journal boxes for said axles, flanges on said journal boxes, and axle hoods connecting the flanges of oppositely placed boxes. 25
15. In a mine car having drop doors, wheels and axles, journal boxes for said axles having hinge lugs and flanges formed integral therewith, and axle hoods connecting the flanges of oppositely placed boxes. 30
16. In a mine car having drop doors, wheels and axles, journal boxes for said axles having hinge lugs and flanges formed integral therewith, latches for said doors mounted on said axles, means pivotally supported by said hinge lugs for operating said latches, and hoods connecting the flanges of oppositely placed journal boxes and shielding said latches and latch operating means. 35
17. In a mine car having drop doors, wheels and axles, journal boxes for said axles having hinge lugs formed integral therewith, latches for said doors mounted on said axles, and means pivotally supported by said hinge lugs for operating said latches. 40
18. In a mine car having sills, wheels and axles, journal boxes for said axles mounted on said sills and having hinge lugs formed integral therewith, drop doors pivotally mounted on said hinge lugs, latches for some of said doors mounted on said axles, and operative 45
- connections between some of said doors and said latches. 50
19. In a mine car having sills, wheels and axles, journal boxes for said axles mounted on the inner faces of said sills and having hinge lugs and flanges formed integral therewith, drop doors pivotally mounted on said hinge lugs, latches for some of said doors mounted on said axles, operative connections between some of said doors and said latches, and hoods for said latches connecting the flanges of oppositely placed journal boxes. 55
20. In a mine car having sills, wheels and axles, journal boxes for said axles mounted on the inner faces of said sills and having hinge lugs and flanges formed integral therewith, drop doors pivotally mounted on said hinge lugs, latches for some of said doors mounted on said axles, operative connections between some of said doors and said latches, means connecting the latches on each axle and holding said latches operatively connected to their operating doors, and hoods for said latches connecting the flanges of oppositely placed journal boxes. 60
